DAVID W. BROOKS, OF NEW YORK, N. Y., ASSIGNOR TO CONCRETE STEEL COMPANY,
OF NEW YORK, N. Y., A CORPORATION OF DELAWARE.

TIE-CLIP.

1,185,764.

Specification of Letters Patent.

Patented June 6, 1916.

Application filed February 9, 1914. Serial No. 817,426.

To all whom it may concern:

Be it known that I, DAVID W. BROOKS, a citizen of the United States of America, residing in New York city, county and State 5 of New York, have invented an Improvement in Tie-Clips, of which the following description, in connection with the accompanying drawings, is a specification, like letters on the drawings representing like 10 parts.

The present invention relates to an improvement in tie clips for use in concrete construction, the object being to provide a clip having wider adaptability than those 15 heretofore in use, and one which is easily and economically manufactured on account of its simplicity of construction.

One embodiment of my invention is illustrated in the drawings which accompany 20 this specification in which,

Figure 1 is a view in perspective, Fig. 2, a similar view showing the clip applied to contiguous bars, and Figs. 3 and 4 are views corresponding to the above and illustrating 25 a modified form.

The clip shown in Figs. 1 and 2 comprises a strip of wire bent to form coöoperating hook portions 1 and 2 which are adapted to engage a pair of contiguous members 3 and 30 4, such as structural bars for concrete. As the clip is applied, one hook portion engages the outer surface of each bar at a place adjacent to their point of contact so that when the distance between the inner 35 contact surfaces of the hook portions is slightly less than that between the corresponding outer surfaces of the bars, the latter are held securely together. In order that the clip may retain its proper position on 40 the bars, it is further provided with runs 5 and 6 having spring portions 9 starting from the continuous sides of the hook portions 1 and 2 respectively. These runs are equipped with hooks 7 and 8 adapted to engage the 45 bars 3 and 4 after the runs have been sprung into operative position against resistance of the spring portions 9.

To attach a tie clip such as I have here described, one of the hook portions is caught 50 under the bar farthest from the operator. The clip is then swung in an arc and twisted so that the other hook will engage the near bar. To complete the operation, the runs are sprung out of normal position and

secured to their respective bars by means of 55 the hooks 7 and 8, except in the case of the modified form of clip referred to below in which both of the runs coöperate with the same bar.

I am familiar with the type of tie clips 60 provided with loops near the point of contact of the bars and which inclose one or both of the bars; but the present construction embodies the principle of the open side clip which may be applied more readily than 65 the loop ties.

The modification illustrated in Figs. 3 and 4, shows the runs 5 and 6 formed so that the hooks 7 and 8 upon their ends will engage the same bar instead of one hook engaging each 70 of the bars. This particular form furnishes a very compact device which is convenient to apply and very easy to pack for shipment.

A further function of clips of the kind shown in the drawings presented herewith 75 is to support the frame work of steel bars out of contact with the forms in connection with which they are erected in order that the steel reinforce may occupy its proper position in the concrete. This object is attained by providing a loop or projecting convolution in the wire, as 10, shown in Figs. 1 and 2, which holds the bar 3 the required distance away from the surface of the form.

It will be understood that the supporting 85 element here described may be formed as a part of the hook portions as well as of the run or may be incorporated into the device in any other suitable manner; and it is further contemplated that various forms of 90 hooks may be substituted for those here shown without departing from the spirit of the invention.

I claim as my invention:-

1. A tie clip for fastening crossed reinforcing rods in concrete construction, comprising a central portion having rod engaging hooks disposed at opposite ends thereof and substantially at right angles to each other, and means for locking said rod engaging hooks in operative position.

2. A tie clip for fastening crossed reinforcing rods in concrete construction, comprising a central portion having rod engaging hooks disposed at opposite ends 105 thereof and substantially at right angles to each other, means for spacing the lower rod from an adjacent support or form and means

for locking said rod engaging hooks in operative position.

3. A tie clip for fastening crossed rods in a reinforced concrete construction, comprising a resilient metallic structure whose central portion is fashioned into two or more rod engaging hooks substantially at right angles to each other, said hooks being provided with extensions therefrom constitut-

ing means for locking them in operative position.

In testimony whereof, I have signed my name to this specification, in the presence of two subscribing witnesses.

DAVID W. BROOKS.
